LOCOMOTIVE STOP VALVE

Application filed December 8, 1928. Serial No. 324,766.

This invention relates to locomotives and especially to stop valves located in the steam dome and used for the purpose of shutting off the steam from the steam chests under certain condition. The invention has particular utility in cases where the main throttle which controls the flow of steam from the boiler to the steam chests is located in the path or paths between the superheater and the steam chests. In such cases it becomes desirable under some conditions to have an additional means on the inlet side of the superheater for shutting off the steam at this point. The invention has for its purpose the provision of improved stop valves for this purpose.

The invention is illustrated in the drawing herewith, in which Fig. 1 shows a fragmentary, central, longitudinal, vertical section of a locomotive with my invention applied; Fig. 2 is an enlarged view of the portions of Fig. 1 more intimately connected with the invention; Fig. 3 is a section on line 3—3 of Fig. 2, and Fig. 4 is a section on line 4—4 of Fig. 2.

The boiler shell appears in Fig. 1 at 1, the smoke-box sheet showing at 2. 3 is the flue sheet separating the boiler space from the smoke-box. 4 is the steam dome. The superheater header is shown at 5. It is believed unnecessary to illustrate the details of the header or the superheater units themselves as the header and the units may be of any preferred construction and form no part of the invention. 6 is the dry pipe leading from the dome 4 to the superheater header 5. At 7 appears one of the steam pipes which carry the steam to the two valve chests. In the form illustrated, the flow of the steam from the superheater header 5 to the valve chests is controlled by a series of valves, one of which shows at 8. Their movement is produced by means of the throttle rod 9 moving lever 10.

The part embodying my invention is the valve at the entrance 11 of the steam pipe 6. The valve proper 12, it will be noted, is disc-shaped and in its seated position engages the upper edge of the opening 11 of the steam pipe 6. On the disc 12 are formed two parallel lugs or ears 13—13, each provided

with two vertical slots 14—14. Extending through these vertical slots are the pins 15—15. These pins also extend through holes in the links 16—16 of which there are four extending in an upward direction. The upper ends of these links have extending through them pins 17—17. These pins 17—17 also extend through holes in the two blocks 18—18 lying between the links. The blocks 18—18 have internal right and left screw-threads engaging corresponding left and right screw threads 19—19 on the spindle 20. At the center of the spindle between flanges 21—21 is a portion 32 on the spindle 20 which is not threaded and against which bears the curved support 33. This support is held in place by the two screws 34—34 inserted from the outside of the cover 23. The purpose of this support 33 is to prevent springing of the spindle when the pilot valve 28 and the main valve 12 are raised. The spindle 20 passes through a stuffing box 22 screwed into the side of the dome cover 23, the opposite end 24 engaging a bearing 25 located in the inner wall of the dome cover. On the underside of the cover there are stops 26—26 to limit the upward movement of the valve.

The upper ends of the links 16—16 lie between the sides 35—35 of the elongated recess in the cover 23. The advantage of this is that it obviates the necessity of any cotter pins in connection with the pins 17—17. When once in place these pins cannot come out.

The upper sides of the blocks 18—18 bear against the straight surface 36 on the inner side of the cover. When the valves are seated, upward thrust on the blocks is thus taken up.

The central part of the disc valve 12 has in it a port 27 controlled by the pilot valve 28. This pilot valve has two upwardly extending lugs or ears 29, through which the pins 15—15 also pass.

The cover 23 is secured in place on its opening in the steam dome 4 by studs and nuts 30—30.

In the center of the upper side of the cover 23 a threaded opening 31 is provided for con-

venient insertion of an eye-bolt or other means for lifting the cover.

The spindle 20 is actuated by any preferred means. It is shown squared at the end so that a hand-wheel may be put in place. Preferably, however, such a hand-wheel is not permanently attached as it would extend above the contour of the dome beyond the allowable clearances. Ordinarily a wrench 10 would be sufficient for turning the spindle.

The operation of this device may be briefly stated as follows: A turning movement of the spindle in one direction will cause the blocks to move from the position indicated in Fig. 2 15 to that indicated in Fig. 1, the turning movement in the opposite direction resulting in opposite travel of the blocks. When the blocks move as first stated, that is, outward from the position indicated in Fig. 2, the first 20 portion of the motion will lift the pilot valve 28 as there is no intentional play between the pins 15-15 and the openings in the ears 29. No motion of the disc valve 12 will occur until the pins 15-15 have reached the upper 25 ends of the slots 14-14. The lifting of the pilot valve 28 allows steam to flow into pipe 6 and the cavities connected to it thereby balancing the disc valve 12. Upon further motion of the spindle in the same direction and 30 further consequent outward travel of the blocks 18, 18, the pins 15-15 engage the upper ends of the slots 14-14 and lift valve 12. The stops 26-26 are preferably of such 35 dimensions that the disc-valve 12 comes into contact with them before the blocks 18-18 reach the possible limit of their outward travel.

To close the valve the spindle is rotated in the opposite direction, the two blocks 18-18 40 move inward, and the disc valve is thus lowered to its seat. The last portion of the motion permits the pilot valve 28 to become seated.

It will be obvious from the illustration that 45 due to the toggle action a great force can, if necessary, be exerted in either first raising or finally closing the valve. This may be of advantage, for example in opening the valve if the valve should for some reason or 50 other, such as a leak on the outlet side, be imperfectly balanced.

It will be noted that there is no vertical spindle in my arrangement which might under some conditions interfere with the 55 necessary clearances. Neither is there a spindle extending through the side of the dome which is an objectionable feature in some prior constructions. The valve according to my invention is extremely compact and requires no enlargement of the 60 dome nor does it introduce any complication in connection with the standpipe. It is very simple in construction and readily accessible for maintenance and repair.

65 I claim:

1. In apparatus of the class described, the combination of a locomotive steam dome, a dry pipe inlet within the dome, a ported valve controlling said inlet, two pairs of slotted lugs on the valve, a pilot valve controlling 70 said port, apertured lugs on the pilot valve, two pins snugly engaging the apertures of the pilot valve lugs and slideably engaging the slots of the valve lugs, a dome cover having an elongated recess on its lower side, a horizontal screw with left and right hand threads mounted longitudinally in the recess and extending through the side of the cover, two blocks on said threads respectively and 75 slideably engaging the sides and bottom of said recess, links pivotally engaging the blocks and the pins, whereby beginning with valve and pilot valve both closed rotary motion of the screw in one direction first raises the pilot valve and thereafter the valve, and rotary movement in the opposite direction again closes both valves.

2. In apparatus of the class described the combination of a steam dome with an opening at its top, a cover for said opening, a dry pipe in the steam dome with its open end opposite the dome opening, a disk valve adapted to close said dry-pipe opening, said cover having an elongated recess on its lower side, a right-and-left hand screw mounted in 90 said recess and extending through the side of the cover, two blocks engaging the right and left hand threads of said screw respectively and slidably engaging the sides and bottom of said recess, and links pivotally engaging 95 the blocks and the valve.

FREDERICK BENGER.
